AIR DISTRIBUTION UNIT FOR ROOF-MOUNTED VEHICLE AIR CONDITIONER

Millard Fillmore Harty, Jr., Bloomfield Hills, Mich., assignor to Motor Wheel Corporation, Lansing, Mich.

Filed Aug. 25, 1971, Ser. No. 175,015

Term of patent 14 years

U.S. Cl. D23—142 Int. Cl. D23—04

FIG. 1

FIG. 2

FIG. 3

FIG. 4

FIG. 5

FIG. 1 is a perspective view of my new design of an air distribution unit for roof-mounted vehicle air conditioner as viewed from the exterior thereof.

FIG. 2 is a vertical elevational view showing one of the outlet ends of the air distribution unit for roof-mounted vehicle air conditioner shown in FIG. 1, the opposite outlet end being identical in appearance.

FIG. 3 is a plan view of the air distribution unit shown in FIG. 1.

FIG. 4 is a vertical side elevational view showing the right side of the air distribution unit for roof-mounted vehicle air conditioner as viewed in FIG. 3.

FIG. 5 is a vertical side elevational view showing the

left side of the air distribution unit for roof-mounted vehicle air conditioner as viewed in FIG. 3.

I claim:

The ornamental design for an air distribution unit for roof-mounted vehicle air conditioner, substantially as shown.
